United States Patent Office.

ADOLPH SCHLINGMAN, OF ALEXANDRIA, OHIO.

Letters Patent No. 73,052, dated January 7, 1868.

IMPROVED BED-BOTTOM.

The Schedule referred to in these Letters Patent and making part of the same.

TO WHOM IT MAY CONCERN:

Be it known that I, ADOLPH SCHLINGMAN, of Alexandria, Preble county, Ohio, have invented a new and useful Bed-Bottom; and do hereby declare the following to be a full, clear, and exact description thereof, reference being had to the accompanying drawings, making part of this specification.

My invention relates to a cheap, easily-adjusted, and highly-elastic bottom for beds. In the accompanying drawings—

Figure 1 represents portions of the head, foot, and one side of a bedstead provided with my improved bottom.

Figure 2 shows a modification of my tightening-device.

A represents the head, B the foot, and C one side of a bedstead, which may be of the kind patented to me on the 30th of April, 1867, or of any approved form. The ends of the foot-rail D of the bed-bottom enter sockets in the sides, which, when my aforesaid patent is employed, may be partially formed by the wedges X, that attach the foot and sides. This rail D may be a flat slab, as represented. The head-rail E of the bottom is a cylindrical piece of timber, terminating in gudgeons e, that occupy suitable sockets in the sides. Both head and foot-rails are provided with customary pins, d, around which the cord F is passed in longitudinally-parallel series, being also rove through perforated and flexible cross-slats G¹ G² G³ G⁴, in the manner shown. Where the bottom is designed for the use of adults, I also add stiffening-slats H, which, being introduced above the head and foot-slats G¹ G⁴, and below the intermediate ones, serve to sustain the extreme edges of the bottom, and to prevent any undue sagging, when the bottom may be unequally loaded, on its respective sides. The head-rail E has two ratchet-wheels, I, which receive pawls J. The cord being rove, as above, through the cross-slats and around the pins, is tightened by rotating the rail E in direction of the arrow, and the pawls J hold it to the desired adjustment. The cross-slats are effective to prevent undue sagging of any one part, and also to prevent the lateral spreading or separation of the individual stretches of cord by a heavy load on one part. The cross-slats G¹ G² G³ G⁴ may be shifted toward the head or foot or middle, so as to stiffen or slacken the bottom at any desired part. A modification of my tightening-device is seen at fig. 2, where D is the foot-rail and K is a stretcher-rail, having horizontal perforations, K, through which the cord is rove, and semicircular bosses L for the bight of the cord, and around which it is readily drawn without undue fraying or wearing. M are screw-bolts, by which the rail is drawn back. This form is preferably employed in all bedsteads where the height of the roller E would be objectionable.

I claim herein as new, and of my invention—

1. A bed-bottom, consisting of the cord F and transverse perforated slats G¹ G² G³ G⁴, with or without the longitudinal stiffening-slats H, the cord being roved forth and back through said slats, and held at the ends by pins, substantially as described and represented.

2. The combination, with the cord F and transverse G¹ G² G³ G⁴, of an adjusting or tightening-rail E or K, applied and operating substantially as described and represented.

In testimony of which invention, I hereunto set my hand.

ADOLPH SCHLINGMAN.
